UNITED STATES PATENT OFFICE.

THOMAS B. BENNETT, OF MUSKEGON, MICHIGAN, ASSIGNOR TO BENNETT PUMPS CORPORATION, OF MUSKEGON, MICHIGAN, A CORPORATION OF MICHIGAN.

OIL-PUMP DRAIN PIPE.

Application filed November 18, 1926. Serial No. 149,060.

This invention relates to an oil pump and is more particularly concerned with an improvement in oil pumps by means of which any dripping of oil from the pump may be returned to the receptacle from which it is withdrawn. It is common practice to apply pumps to barrels or casks in which a considerable quantity of oil is contained and to pump therefrom into a measuring can or receptacle from which it is transferred directly to the mechanism lubricated. When the pump is stopped and the can or receptacle removed from below the pump outlet there is liable to be dripping of oil. It is to catch such dripping and return the same to the barrel or cask on which the pump is installed that I have made the present invention, thereby obviating loss of oil and avoiding messy conditions due to oil over the upper end of the barrel or cask.

The invention which I have made is simple yet very practical and useful, being readily applied to an oil pump of the character outlined. A drain pipe is normally located underneath the delivery end of the pump outlet and is automatically moved from such position by the receptacle into which oil is pumped when it is placed under such outlet, but as soon as the receptacle is removed the drain pipe moves back to its normal operative position. The construction which I have devised for this purpose is fully set forth in the following description and shown in the accompanying drawing, in which:

Fig. 1 is an elevation showing an oil pump with my invention applied thereto, the drip collecting pipe being moved out of the way by an oil receiving receptacle located underneath the outlet of the pump.

Fig. 2 is a fragmentary enlarged elevation, with parts broken away and shown in section, showing the manner in which the drip collecting pipe is mounted on the pump and used, and

Fig. 3 is a vertical transverse section substantially on the plane of line 3—3 of Fig. 2. Like reference characters refer to like parts in the different figures of the drawings.

The pump may be of any usual construction comprising a cylinder 1 at the upper end of which is a head 2 carrying a crank 3 which is hand operated so as to move the pump piston back and forth in the cylinder

in the usual manner, this being well known and not being illustrated in the drawing. The oil which is pumped passes upwardly through an extension 4 above the head 2 and is delivered therefrom laterally through a nipple 5 into the delivery or outlet member 6.

This delivery or outlet member 6 is hollow, the nipple 5 threading into one end thereof. The opposite end is closed and a short outlet tube 7 is secured near the outer end of the member and passes through the lower side so that the oil may escape through this tube. On the under side of the member 6 it is provided with spaced apart integrally cast depending sides 8 the inner ends of which are connected by a cross member 9 and the outer ends joined with a substantially cylindrical wall 10 located around and extending below the lower end of the outlet tube 7 described.

At the lower end of the cylinder is a second head 11 which is formed in its upper portion with a downwardly tapered valve seat 12 in which a ball 13 is located, the same serving to cooperate with an opening leading to a pipe 14 which extends downwardly into a barrel or cask 15 on which the pump is mounted. The mounting is in any suitable manner, the lower end of the head 11 being threaded preferably to screw into a suitable opening in the upper side of the barrel as indicated at 16.

The head 11 at one side is provided with an integrally formed elbow 17 which is hollow and which at its lower portion communicates with the interior of the barrel or cask 15 so that any oil coming to the elbow 17 is returned to the barrel or cask around the pipe 14. The upper end of the elbow 17 has a relatively large opening and is machined so as to make portions of a curved or ball surface, as indicated at 17^a, the purpose of which will later appear.

A drip pipe 18 is provided having an intermediate straight portion normally inclined to the vertical and the lower end 18^a bent at an angle thereto and normally positioned vertical, its lower end passing into the opening in the upper end of the elbow 17. A pin 19 passes through the elbow 17 and the lower end of the pipe 18 whereby the pipe is permitted to turn on a horizontal axis. The lower section 18^a of the pipe is equipped with a cap 20 which is shaped so

that it fits securely against the curved or round surface of the part 17^a, covering the opening into which the lower end of the pipe is inserted. A spring 21 may be attached to the cylinder 1 or to the binding rods which bind the head 2 and 11 against the ends of said cylinder, bearing at its free upper end against the pipe and normally holding the pipe in outer position.

10 The upper end of the pipe includes a normally vertically positioned section 18^b bent at an angle from the intermediate main and longer section of the pipe. This upper end of the pipe is received in the space surrounded by the spaced apart sides 8, the end 9 and the end 10 depending from the outlet member 6. The upper end of the pipe therefore has a limited movement between the two ends 9 and 10 and can not move laterally 20 being held against such movement by the sides 8 as is evident.

When the pump is not in use the spring 21 holds the pipe in outer position, as shown in Fig. 2, with its upper end directly below the outlet tube or sleeve 7. When the pump is to be used a receptacle for receiving oil, such as indicated at 22 in Fig. 1, is placed against the drip pipe and moves it back toward the pump as shown in Fig. 1. The 30 pump may then be operated so as to fill the receptacle at 22. When it is filled and operation of the pump stopped and the receptacle taken away, its removal frees the drip pipe which immediately returns to the position 35 shown in Fig. 2 or under the outlet sleeve 7, so that any oil dripping from this sleeve is carried back through the drip pipe to the sleeve 7 and thence to the barrel or cask 15 from which it was withdrawn.

40 The construction described is very practical, is a simple and economical construction to make and is easily assembled so that the cost of manufacture is low. While a spring 21 is shown and described for the purpose stated, such spring is not absolutely necessary as it is the normal tendency of the pipe to move to its outer position by gravity. The spring therefore is for additional assurance when it is used and in many cases it is not 50 used at all. The invention is defined in the appended claims and is to be considered com-

prehensive of all forms of structure coming within their scope.

I claim:

1. In combination with an oil pump having an outlet nozzle, a movable drain pipe having an end adapted to be moved into association with said nozzle to receive oil therefrom and also adapted to be moved away from said nozzle and means for covering said open end of the drain pipe when it is moved away from said nozzle. 55

2. In combination with an oil pump having an outlet nozzle, a movable drain pipe having an open end adapted to be moved into association with said nozzle to receive oil therefrom and also to be moved away from said nozzle and a fixed guard arranged to cover the open end of said drain pipe at any of its positions away from said nozzle. 65 70

3. In combination with an oil pump having an outlet nozzle, a movable drain pipe having an open end adapted to be moved into association with said nozzle to receive oil therefrom and also to be moved away from said nozzle; a fixed guard arranged to cover the open end of said drain pipe at any of its positions away from said nozzle, and guide members associated with said guard to guide and limit said drain pipe in its movements. 75 80

4. In combination with an oil pump, a channel having continuous sides and ends, an outlet nozzle of said oil pump located within said channel and a drain pipe having a movable open end irremovably located in said channel and adapted to traverse the same from a position in association with said nozzle to receive oil therefrom to a position away from said nozzle. 85 90

5. In combination with an oil pump, a downwardly opening channel having continuous sides and ends, an outlet nozzle of said pump extending into said channel and a drain pipe having a movable upwardly opening end irremovably located within said channel and adapted to be moved to a position in association with said nozzle to receive oil therefrom and to a position away from said nozzle. 95 100

In testimony whereof I affix my signature.

THOMAS B. BENNETT.
